(57) **CLAIM**

The ornamental design for a toy block cluster, as shown and described.

DESCRIPTION

FIG. 1 is a front view of a toy block cluster incorporating a design in accordance with a first embodiment of the present disclosure;

FIG. 2 is a top view thereof;

FIG. 3 is a rear view thereof; and

FIG. 4 is a left side view thereof.

FIG. 5 is a front view of a toy block cluster incorporating a design in accordance with a second embodiment of the present disclosure;

FIG. 6 is a top view thereof;

FIG. 7 is a rear view thereof; and

FIG. 8 is a left side view thereof.

FIG. 9 is a front view of a toy block cluster incorporating a design in accordance with a third embodiment of the present disclosure;

FIG. 10 is a top view thereof;

FIG. 11 is a rear view thereof; and

FIG. 12 is a left side view thereof.

FIG. 13 is a front view of a toy block cluster incorporating a design in accordance with a fourth embodiment of the present disclosure;

FIG. 14 is a top view thereof;

FIG. 15 is a rear view thereof; and

FIG. 16 is a left side view thereof.

FIG. 17 is a front view of a toy block cluster incorporating a design in accordance with a fifth embodiment of the present disclosure;

FIG. 18 is a top view thereof;

FIG. 19 is a rear view thereof; and

FIG. 20 is a left side view thereof.

FIG. 21 is a front view of a toy block cluster incorporating a design in accordance with a sixth embodiment of the present disclosure;

FIG. 22 is a top view thereof;

FIG. 23 is a rear view thereof; and

FIG. 24 is a left side view thereof.

FIG. 25 is a front view of a toy block cluster comprising a first set of blocks incorporated in a top portion thereof and a second set of blocks incorporated in a bottom portion thereof in accordance with a seventh embodiment of the present disclosure;

FIG. 26 is a top view thereof;

FIG. 27 is a rear view thereof; and

FIG. 28 is a left side view thereof.

The broken lines in FIGS. 25, 27 and 28 represent the bounds of the claim and indicate the appearance of any portion of the article between the boundary lines forms no part of the claimed design.
